Patented Dec. 10, 1957

181,623

AWNING SLAT

Oscar Brand, St. Louis, Mo., assignor to Arcraft Venetian
Blind Mfg. Company, St. Louis, Mo., a corporation of Missouri

Application December 12, 1956, Serial No. 44,168

Term of patent 14 years

(Cl. D21—6)

I claim:

The ornamental design for an awning slat substantially as shown.
